(57) **CLAIM**

The ornamental design for a front bumper for a vehicle, as shown and described.

DESCRIPTION

This application contains subject matter related to the following co-pending U.S. design patent applications:

Application Ser. No. 29/594,693, filed Feb. 22, 2017 and entitled "Front Bumper For a Vehicle";

Application Ser. No. 29/624,723, filed Nov. 3, 2017 and entitled "Front Bumper For a Vehicle"; and

Application Ser. No. 29/631,776, filed herewith and entitled "Front Bumper For a Vehicle".

FIG. 1 is a front view of a front bumper for a vehicle according to the design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.
